CLAIM

The ornamental design for a wall mounted adhesive melter, as shown and described.

DESCRIPTION

FIG. 1 is a perspective view of the wall mounted adhesive melter according to a first embodiment of the present invention.

FIG. 2 is a front elevational view of the wall mounted adhesive melter according to the first embodiment of the invention. FIG. 3 is a right side elevational view of the wall mounted adhesive melter according to the first embodiment of the invention.

FIG. 4 is a rear side elevational view of the wall mounted adhesive melter according to the first embodiment of the invention.

FIG. 5 is a left side elevational view of the wall mounted adhesive melter according to the first embodiment of the invention.

FIG. 6 is a top elevational view of the wall mounted adhesive melter according to the first embodiment of the invention.

FIG. 7 is a bottom elevational view of the wall mounted adhesive melter according to the first embodiment of the invention.

FIG. 8 is a perspective view of the wall mounted adhesive melter according to a second embodiment of the present invention.

FIG. 9 is a front elevational view of the wall mounted adhesive melter according to the second embodiment of the invention.

FIG. 10 is a right side elevational view of the wall mounted adhesive melter according to the second embodiment of the invention.

FIG. 11 is a rear side elevational view of the wall mounted adhesive melter according to the second embodiment of the invention.

FIG. 12 is a left side elevational view of the wall mounted adhesive melter according to the second embodiment of the invention.

FIG. 13 is a top elevational view of the wall mounted adhesive melter according to the second embodiment of the invention; and,

FIG. 14 is a bottom elevational view of the wall mounted adhesive melter according to the second embodiment of the invention.

The broken lines define unclaimed boundaries of the design.
